UNITED STATES PATENT OFFICE.

CATHARINE LEHBERGER, OF NEWARK, NEW JERSEY.

GARBAGE RECEPTACLE.

Application filed January 31, 1924. Serial No. 689,793.

To all whom it may concern:

Be it known that I, CATHARINE LEHBERGER, a citizen of the United States, and residing at Newark, in the county of Essex and State of New Jersey, have invented certain new and useful Improvements in Garbage Receptacles, of which the following is a specification.

This invention relates to improvements in receptacles for refuse and waste commodities, such as garbage, ashes and the like, the same being temporarily contained therein until a convenient time for their eventual disposition.

One of the objects of the invention is to provide a receptacle having a normally closed cover that can be opened in an instant and ready manner by contact of the foot against the bail or handle when it is desired to enter articles.

Another purpose is to produce a receptacle in which the cover is automatically opened by manipulating the container when discharging its contents.

A further aim is in the provision of a strong, neat appearing can that can be used without soiling the hands or clothing and which is relatively inexpensive to construct.

These several aims and objects are accomplished by the novel construction and arrangement of parts hereinafter described and shown in the accompanying drawing, forming part of this disclosure, and in which:—

Figure 1 is a perspective view of an embodiment of the invention showing the cover closed.

Figure 2 is a partial side elevational view of the same.

Figure 3 is a similar fragmentary view showing the cover in a raised position.

Figure 4 is a side view of the complete can showing a modified means for attaching the fixed portion of the cover.

Referring more in detail to the drawing, the numeral 10 designates a cylindrical metal can, of any preferred dimension, having a beaded bottom 11 and a pair of ears 12 secured by rivets 13, these ears being bent to stand away from the can sides and are provided with the usual openings for receiving the bail.

Said bail 14 may be a semi-circularly bent wire, or have a handle loop 14' as pre-

ferred, its ends 15 being inturned to engage 55 in the ears 12.

On one side of the can is attached a handle 16, that side being considered as the back, the handle being midway between the ears.

A partial lid or cover 17 is secured by a bead 18 enshrouding the bead 19 enclosing a wire surrounding the top of the can, stiffening and re-enforcing the same.

The inner, chordal edge of the fixed cover element is provided with extensions that are coiled to produce hinge elements 20 encircling the hinge pin 21, two of which are preferably employed and having adjacent them similarly coiled elements 22 formed 70 on the movable cover 23; a stop 24 is also integrally formed on the fixed cover limiting the opening movement of the hinged portion of the cover.

A skirt like depending flange 25 is formed 75 on the cover 23, the same having a partial bead 26 at its edges, the flange 25 being widened as at 27 at opposite points directly over the ears 12 and the ends of the widened or broadened portions of the flange 80 are curved slightly upward as at 28.

A pair of cam-like plate elements 29, generally triangular in contour, are attached to the bail 14 by rigidly engaging in looped eyes 30 formed on the plates, 85 the bail passing therethrough near their pivotal elements 15 which also pass through the plates as clearly shown.

In-reaching curved lugs or cams 31 extend towards the can body in position to 90 normally make contact with the elements 28 of the cover and disposed at right angles thereto are similar in-reaching lugs or cams 32 adapted to make contact with the forward ends of the elements 27 when the position of the bail is reversed.

The normal position of the parts, when the cover is completely closed is shown in Figures 1 and 2 and it will be obvious that upon depressing the bail from its substantially horizontal position, as by contact with a person's foot, the hinged portion of the cover will be raised as shown in Figure 3, to remain open, against the stop 24 until the same is touched by the foot or otherwise 105 closed.

When the bail is used in carrying the receptacle it will be vertical and central,

as is apparent, neither of the cams, at that time being in contact with the outstanding flange.

The contents are removed by grasping the handle 16, the bail 14, being turned into a reversed position as shown in Figure 4, at which time the cam lugs 32 make contact with the flanges 27, opening the hinged cover and presenting no obstruction to the passage of material outward, the can being then in a tilted position.

In the modification, shown in Figure 4 the cover element 17, in place of being permanently secured by the beading, is provided with outwardly extending lugs 33 formed integrally along its edges, the same extending over correspondingly formed rectangular lugs 34 formed on the metal can 10, the cover element 17 and said can 10, being removably secured together by means of thumb bolts 35 passing through the lugs 33 and engaging with the lugs 34.

This arrangement provides a rigid fastening for the cover elements, but permits the same to be removed, as a unit, if desired.

While certain preferred embodiments of this device have been shown and described, it will be understood that changes in the form of arrangements, proportions, sizes, and details thereof may be made without departing from the scope of the invention as defined in the appended claims.

Having thus described my invention, what I claim as new and desire to secure by Letters Patent, is:—

35

1. A can having a pair of ears, a bail pivotally connected thereto, of a sectional cover, one section being rigidly connected to the can and the other section hinged to the first named section, flanges on the hinged section and extending outwardly over said ears, cam plates fixed to said bail and adapted for engagement with the said flanges to raise the said cover, when the bail is depressed in one direction and to raise said cover when the bail is depressed in the opposite direction.

40

2. A can having a pair of ears, a bail pivotally connected to said ears, of a sectional cover, one section rigidly connected to said can and the other section hinged to the first named section, flanges on the said hinged section, cam plates fixed to said bail and adapted for engagement with the said cover flanges to elevate the hinged section, when the said bail is adjusted in opposite directions.

45

This specification signed and witnessed this 28 day of January, 1924.

CATHARINE LEHBERGER.
